UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

HOLDING SHEETS IN REGISTER ON TAPE CARRIERS.

Application filed October 2, 1923. Serial No. 666,132.

It has been very difficult to accurately feed sheets cut from light weight and loosely woven fabric webs. This has been especially true in the case of burlap because of the 5 tendency of the material to wrinkle.

The object of my invention is to provide means coacting with an endless sheet feeding tape carrier for engaging the advance edge of the sheet as it is cut from the web 10 and to maintain contact with the sheet until it is received by the sheet taking means, thereby ensuring the proper feeding of the sheets in register to the said sheet taking means.

15 My invention comprises more particularly gravity operated rollers frictionally driven by and coacting with the endless tape carrier to engage and maintain control of the sheet from the time it is cut from the 20 web until it is taken by the sheet taking means.

A practical embodiment of my invention is represented in the accompanying drawings, in which

25 Fig. 1 represents in side elevation a portion of a web cutting and sheet feeding mechanism with my invention applied thereto.

Fig. 2 represents a detail sectional view on 30 an enlarged scale of the sheet feeding mechanism.

Fig. 3 represents a detail plan view of the same.

The web feeding mechanism is herein 35 shown as including the web feed drum 1 and its coacting feed rolls 2. The mechanism for cutting the sheets from the web is shown as comprising the coacting rotary and stationary cutting members 3 and 4. Both the 40 feeding and cutting mechanisms may be driven at the desired speed through suitable intermediate gearing from the main drive shaft 5.

The sheet taking mechanism is herein 45 shown as a rotary cylinder 6 which may be a part of printing or folding mechanism, said cylinder having grippers 7 for taking the leading ends of the sheets as they are fed thereto from the cutting mechanism by 50 the endless sheet carriers 8 and 9. The tapes of the upper tape carrier pass around pulleys 10 at the receiving end of the carrier and around pulleys 11 at the delivery end thereof. The tapes of the lower tape carrier

55 pass around pulleys 12 at the inner end of the carrier and around the roll 13, the pulleys 14 and the roll 15 at the delivery end of the carrier. Suitable sheet guides 16 extend to the surface of the sheet taking cylinder 6.

60 The shaft 17 of the pulleys 11 is provided with a gear 18 meshing with a gear 19 on the shaft of the sheet taking cylinder 6, whereby the upper endless tape carrier is driven at the surface speed of the cylinder. The shaft 65 20 of the pulleys 14 is provided with a gear 21 which is driven through a train of gears 22, 23, 24, 25, 26, 27 from the horizontally arranged shaft 28, which is in turn driven through the gears 29, 30 from the main drive 70 shaft 5.

A bar 31 extends horizontally across the machine, which bar is provided with a plurality of arms 32, the free ends of which are provided with rollers 33 which normally 75 rest by gravity upon the tapes 9 where they pass over the roll 13 of the lower endless tape carrier. These rollers 33 are arranged to coact with the lower endless tape carrier to engage the advance end of the sheet just 80 as it is severed from the web and to maintain control of the sheet until the advance edge of the sheet is grasped by the grippers 7 of the sheet taking cylinder 6. It will thus be seen that the sheet will be fed in 85 register to the sheet taking means.

It is evident that various changes may be resorted to in the construction, form and arrangement of the several parts without departing from the spirit and scope of my invention; hence, I do not wish to be limited to the particular embodiment herein shown and described, but

What I claim is:—

1. Sheet taking means, an endless tape 95 carrier for conveying the sheets to the sheet taking means, a roll over which the tapes of the carrier pass, a transverse support, rock arms carried thereby and rollers carried by said rock arms in position to rest 100 by gravity on the said tapes where they pass over said roll for engaging the advance end of the sheet and to maintain contact with the sheet until it is received by the sheet taking means, to ensure the proper feeding of the 105 sheet in register.

2. Sheet taking means, upper and lower endless tape carriers for feeding the sheets

to the sheet taking means, a roll over which the tapes of the roller tape carrier pass, a transverse support, rock arms carried thereby and rollers carried by said rock arms in position to rest by gravity on the said tapes where they pass over said roll for engaging the advance end of the sheet and maintain

contact with the sheet until it is received by the sheet taking means, to ensure the proper feeding of the sheet in register.

In testimony, that I claim the foregoing as my invention, I have signed my name this 28th day of September A. D. 1923.

HOWARD M. BARBER.
